UNITED STATES PATENT OFFICE.

ALBERT BESS, OF HAMILTON, OHIO.

SLITTER-GRINDER.

SPECIFICATION forming part of Letters Patent No. 766,927, dated August 9, 1904.

Application filed January 23, 1904. Serial No. 190,259. (No model.)

To all whom it may concern:

Be it known that I, ALBERT BESS, a citizen of the United States, residing at Hamilton, Ohio, have invented a new and useful Improvement in Slitter-Grinders, of which the following is a specification.

- My invention relates to slitter-grinders of the class adapted to grind paper-mill slitters or other articles; and the objects of my improvement are to provide means to grind slitters without the necessity of removing them from the rotative shafts whereon they are mounted, to mount a grinding-wheel directly on the shaft of an electric motor which is mounted on a universally-adjustable bracket, and to provide screw-feed mechanism therefor, whereby the grinding-wheel may be adjusted in any angle or position to the object to be ground and moved in contact therewith.
- These objects are attained in the following-described manner, as illustrated in the accompanying drawings, in which—

Figure 1 is a plan of my improved device; Fig. 2, a side elevation while in operative position, and Fig. 3 a longitudinal section of the feed mechanism.

In the drawings, 4 represents the top slitter-blade, and 5 the bottom cup-slitter, mounted, respectively, on rotative shafts 6 and 7 in the ordinary manner. Stationary shaft 8 is removably secured parallel to shafts 6 and 7 and at any desired distance therefrom.

Split sleeve 9 is adjustably secured on shaft 8 and at right angles thereto by means of seat 11, formed therein, and cap 12, which is removably secured thereon with cap-screws 13. Cylindrical arm 14 is clamped in sleeve 9 by means of hand-screw 15 and is longitudinally and rotatively adjustable therein. Split collar 16 is securely fastened to one end of said arm and at right angles thereto by means of transverse pin 17 or otherwise.

Bushing 18 may be maintained in different positions of rotative adjustment within split collar 16 by means of hand-screw 19 in said collar. Lug 21 extends inwardly from one side of said bushing and terminates in a threaded nut 22, concentric with its axis.

Feed-sleeve 23 is formed with a longitudinal slot 24 for the movement therein of lug 21 and

is longitudinally movable within bushing 18 to the extent permitted by the slot. Feed-screw 25, which is extended axially through the sleeve and engages nut 22, serves to actuate the sleeve as desired. Hand-wheel 26 is mounted on one end of the feed-screw, together with collar 27, which prevents any longitudinal movement of the screw within the sleeve.

Flange 28, formed on one end of sleeve 23, serves for a seat whereon electric motor 29 is secured, with its shaft 30, at right angles to the sleeve by means of cap-screws 31. Grinding-wheel 32 is mounted on one end of the motor-shaft, and wires 33 provide the motor with an electric current from a generator. (Not shown.)

In operation the universal adjustment of the bracket by which the motor is attached to shaft 8 permits the grinding-wheel to be placed in any desired angle or position to the slitter and to be fed in contact therewith by means of the screw-feed mechanism.

Slitters may be ground more accurately while in position on their own rotating shaft than after being removed therefrom. Where provision has been made in the construction for the independent rotation of either of the slitter-shafts, the other one may be secured against rotation and used for the attachment thereto of the bracket during the grinding process of the slitters on the other shaft instead of providing a special shaft 8 for the purpose.

Having fully described my improvement, what I claim as my invention, and desire to secure by Letters Patent of the United States, is—

1. The combination with an arm, and means arranged to secure it to a fixed shaft in different positions of longitudinal or rotative adjustments thereon and with the arm in different positions of longitudinal or rotative adjustment, of feed mechanism mounted at right angles and rotatively adjustable on the arm, an electric motor mounted on said mechanism, and a grinding-wheel mounted on the motor-shaft.

2. The combination with an arm, and means arranged to adjustably secure to a fixed shaft,

of screw-feeding mechanism mounted at right angles on the arm and rotatively adjustable, an electric motor secured to said mechanism and a grinding-wheel mounted on the motor-
5 shaft.

3. The combination with a sleeve arranged to be adjustably secured to a fixed shaft and at right angles thereto, an arm adjustably se-

cured in the sleeve, and a collar secured at right angles on the arm, of a bushing adjustable rotatively in the collar, and screw-feed mechanism adjustable axially in the bushing.

ALBERT BESS.
